SLIDER FOR SEPARABLE SLIDE FASTENERS

Filed March 30, 1946

UNITED STATES PATENT OFFICE

2,510,736

SLIDER FOR SEPARABLE SLIDE FASTENERS

Esther E. Bogenberger, Milwaukee, Wis., assignor
of fifty per cent to Joseph J. Helby, Milwaukee,
Wis.

Application March 30, 1946, Serial No. 658,493

1 Claim. (Cl. 24—205.14)

1

This invention relates to improvements in separable fasteners, particularly to fasteners of the interdigitating type such as shown in my previously issued Letters Patent No. 2,278,388, dated March 31, 1942.

An object of the invention is to provide a separable fastener whose casing or interdigitator is so constructed and designed that the same can be slid over and along a surface without impedance from existing irregularities or any which may occur therein, and without liability of catching portions of such irregularities or foreign objects (including parts of the anatomy) between the interdigitating separable fastener elements during a closing operation thereof, as well as during their disengagement or "fastener opening" during sliding of the casing in an opposite direction.

It is also an object of the invention to provide a casing for slide separable fasteners, of the above indicated type, so constructed that its normally leading end will deflect, from its path of travel, any and all foreign objects and/or portions thereof, hence, preventing their becoming caught or engaged between the interdigitated fastener elements with damage to both objects or portions thereof and the fastener elements.

Yet another object of the invention is to provide a separable fastener possessed of durability, operational efficiency, and simple construction, capable of being effected by and with mass production methods and apparatus, with maximum cost economies.

A further and equally important object of the invention is to provide a separable fastener casing or interdigitator wherein the separable fastener elements, in the course of being interengaged thereby, will be caused to enter the normally leading end of the same at points positively removed or spaced from a surface over which said casing is being slidably moved, such surface spaced entry of the fastener elements into the casing being further accentuated by the imparting of an outward pull to the casing caused by the novel placement or connection of a finger engaged piece with said casing, as well as like spacing when the casing is slid in an opposite direction to effect disengagement between the previously interengaged fastener elements.

The foregoing, as well as other objects, advantages and meritorious teachings of my invention, will be in part obvious and in part pointed out in the following detailed disclosure thereof, when taken in conjunction with the accompanying drawings, it being understood that the form

of invention presented herein is precise and what is now considered to be the best mode of embodying its principles, but that modifications and changes may be made in specific embodiments without departing from its essential features.

In the drawings:

Figure 1 is a front elevation of the improved fastener in operative position with relation to the cooperative fastener elements.

Figure 2 is a rear elevation of the same.

Figure 3 is a longitudinal section taken on the line 3—3 of Figure 1.

Figure 4 is a side elevation of the fastener, showing the finger piece in its open position.

Figure 5 is a perspective view of the fastener with the finger piece in raised or open position, and illustrating the formation of said fastener from the normally front or forward side thereof, and

Figure 6 is a similar view taken from the back or rearward side of the fastener.

Referring in detail to the drawings, the improved fastener, generally, comprises a slide body or casing consisting of front and back sides 1 and 2 and a combined finger engaging and fastener element locking piece 3. Said casing is adapted to function or serve as an interdigitator for cooperable oppositely disposed fastener elements 4 fixedly mounted, in equi-spaced relation, on the adjacent marginal portions of tapes 5, or their equivalents, which, in turn, are to be secured by appropriate means to pieces of material 6, etc. By sliding the casing 1—2 in a pre-determined direction, the opposed rows of fastener elements 4 will be and are brought in interlocking (interdigitating) relation, hence, interconnecting the material pieces 6. And by the same token, by the sliding retraction of said casing, the opposed rows of fastener elements 4 are disengaged or separated, thereby disconnecting the pieces 6.

The fastener elements 4, as is known in the art, can be made of metal, plastic or other sufficiently strong and durable material, as conditions or preference may dictate.

The fastener casing, made of metal, plastic or other suitable material, consists, as above stated, of front and back sides 1 and 2.

The front side 1 has inwardly flanged generally longitudinal sides 7, the normally forward or leading portions of which are divergent, as will be seen on reference to Figures 1 and 5 of the accompanying drawings, thus, provide a greater area or width to its normally forward portion. Said forward portion of the side 1 is

reduced or convergent, as indicated at 8, and is formed or otherwise provided with a longitudinally directed dovetail shaped tongue 9, whose outer and free end portion is angularly and outwardly bent, as at 10, and slotted (see Figures 3 and 4) for a purpose hereinafter described.

An intermediate and somewhat rearward portion of the front side of the slide casing has a finger 11 struck outwardly at substantially right angles therefrom.

The slide casing back side 2, as will be appreciated by artisans skilled in the art, constitutes the runner or surface contact member of the improved fastener. It is formed with outwardly flanged generally longitudinal sides 12, whose normally forward or leading portions are divergent (see Figures 2 and 6), and so, provide a greater area or width to its normally forward portion, generally corresponding to though larger than that of the corresponding forward portion of the front side 1. The forward end of the back side 2 is somewhat reduced or convergent, as at 13, and has an intermediately located outwardly or right angularly disposed slotted tongue 14 formed or otherwise provided to the same. This tongue 14, as will be seen on reference to the accompanying drawings, is positioned directly adjacent and substantially parallel to the tongue portion 10 of the front side 1.

If desired, the slotted portions 9 and 14 may be joined or united by solder or other means. However, it is entirely feasible and practicable, from a viewpoint of stamping production, that they may be integral, i. e., the front and back sides 1 and 2, may be made from a single piece of material, and by suitable operations, their respective tongues 9 and 14 may be formed or constituted, as hereinbefore described, and then, transversely bent or stamped intermediately of themselves into the formation or relationship shown in Figures 1, 4, 5 and 6 of the drawings.

The convergent leading end 13 of the back side 2, has opposed portions of its flanges 12 cut away, as indicated at 15, it being noted that said cut away portions, by reason of the convergent forward or leading end of said side 2, are divergently arranged. These divergent cut away portions or ways 15, as shown in Figures 1, 2 and 3 of the drawings, serve to permit slidable introduction or engagement of the opposed rows of cooperable fastener elements 4 therein and their longitudinal sliding movement through the same from the rearward or trailing end of the slide fastener casing 1-2.

To effect individual and relatively spaced and converging entry of the opposed rows of fastener elements 4 into the slide fastener casing via the divergent ways 15 formed in the leading end of its back side 2, and to ensure proper relative positioning and interdigitition of said fastener elements 4 as they enter into said casing via said ways (see Figure 1), the normally forward portion of said back side 2 has an inwardly stamped or depressed portion forming on the opposite or inner face thereof a triangularly shaped guide lug or element 16, whose opposite sides, as indicated in Figures 5 and 6 of the accompanying drawings, are substantially parallel to the opposite sides of the divergent ways 15 formed by adjacent portions of the back side generally longitudinal flanges 12. Thus, individual entry ways are provided to the cooperable separable fastener elements 4, as they enter into and between the sides 1 and 2 of the slide fastener during sliding movement of the latter.

The normally forward and wider portion of the longitudinally flanged back side 2, and particularly, that portion of the same having the guide lug 16 formed therein, as above described, is outwardly and transversely curved, as indicated at 17. Hence, the normally forward or leading portion of said side 2 will be somewhat spaced outwardly or away from the surface over which the slide fastener is to be or is being moved, serving

as an effectual form of buffer with respect to existing irregularities in said surface or any which may occur in the same, and so, avoiding interference with engagement of the separable fastener elements 4 into and through the ways 15, as well as preventing the catching of any portions of such irregularities or other foreign objects, including parts of a person's anatomy, therein.

With a view toward providing the slide fastener with means for effecting the imparting of sliding movement thereto, I provide the finger engaging piece or handle 3, the outer end of which is provided with a suitable finger engaging portion or grip, generally indicated at 18, while its inner end portion is rolled, as at 19, and engaged through the aligned slots of the portions 9 and 14 of the front and back sides 1 and 2 respectively, whereupon said rolled portion is clinched or otherwise secured to prevent disengagement of the handle therefrom, and at the same time, permit of its pivotal movement with relation to the slide fastener casing 1-2. A finger 20 is preferably struck from an appropriate portion of the handle and is so positioned and disposed with relation thereto, that when the handle is pivoted to its closed position, its finger 20 will engage through the opening provided for by the outstriking of the finger 11 and with or between the now interdigitated separable fasteners 4 (see Figure 3), hence, preventing disengagement between said interdigitated fasteners. The pivotal connection of the finger engaging piece or handle 3 to the slide fastener casing 1-2, is, as will be observed upon reference to the figures of the accompanying drawings, effected adjacent its normally forward or leading end. In consequence, when said finger piece 3 is engaged and has a pull imparted thereto whereby to effect its sliding movement with relation to the cooperable fastener elements 4, the forward and transversely curved portion 17 of the back side 2, will be moved, for a limited distance, outwardly from or with relation to the rows of cooperable fastener elements 4 and the surface of an object adjacent the same. In consequence, as forward pull is imparted to the slide fastener through the forwardly pivotally connected handle 3, the rows of separable fastener elements 4 will enter into and through the ways 15 of the forward end of the back side 2 in definitely outwardly spaced relation to the surface of an object adjacent said fastener elements 4, and so, the undesired catching, pinching or other engagement of portions of said objects in and between the cooperable fastener elements 4 during their period of interdigititation or interconnection will be positively prevented. Moreover, the transversely curved normally forward buffer portion of the side 2 of the slide fastener will definitely improve or better the ease with which said slide fastener may be moved in a direction to effect interdigititation between the separable fastener elements 4.

Also, it will be understood and appreciated that when the handle or finger piece 3 of the slide fastener is engaged and moved in a direction to effect sliding retraction of the fastener (slid-

able movement in an opposite direction to that above described), the outward pull imparted to the hereinbefore described portion of the casing will again effect its definite spacing from a surface over which it is to be or will be drawn. In consequence, said casing will be allowed free sliding travel without interference with or impedance from adjacent irregularities or foreign objects.

I claim:

A slider for a slide fastener, comprising a body consisting of substantially opposed and relatively spaced longitudinally flanged front and back sides, the forward end of the front side being reduced in width, a longitudinally disposed dovetail shaped tongue of less width than the front side integral with and extended from an intermediate portion of the reduced end of said front side overlying the forward portion of the back side, the free end portion of said tongue being bent outwardly from the body thereof, said front side and tongue being substantially straight throughout the combined lengths thereof, the back side having its forward portion curved outwardly and toward the forward end of the front side and the dovetail shaped tongue and completely overlying the same, a tongue extended

outwardly from an intermediate portion of the forward end of the back side adjacent and substantially parallel to the bent free end portion of said dovetail shaped tongue, said outwardly extended tongue and bent free portion of said dovetail shaped tongue disposed outwardly beyond and laterally of the outer side of the front side, and a finger engaging means swingably connected to said outwardly extended tongue and free end portion of said dovetail shaped tongue outwardly of the outer side of said front side.
